(57) CLAIM

The ornamental design for a pot wrap holder, as shown and described.

DESCRIPTION

FIG. 1 is a plan view, the opposite side being a mirror image of a pot wrap holder showing my new design;

FIG. 2 is a top view thereof;

FIG. 3 is a perspective view thereof, showing the pot wrap holder affixed to a pot, which is shown in environmental lines; and,

FIG. 4 is a partial perspective rear view thereof.

The views of the pot wrap holder not shown form no part of the claimed design. The broken lines depicting the optional duplicate holder within the same pot wrap, the remainder of the pot wrap, the tongue and groove sections and the pot represent environmental elements only and form no part of the claimed design.
